UNITED STATES PATENT OFFICE.

STEPHEN H. KIMBALL, OF EVERETT, MASSACHUSETTS.

VELOCIPED.

SPECIFICATION forming part of Letters Patent No. 278,972, dated June 5, 1883.

Application filed August 25, 1882. (No model.)

To all whom it may concern:

Be it known that I, STEPHEN H. KIMBALL, of Everett, in the county of Middlesex and State of Massachusetts, have invented certain 5 Improvements in Velocipedes, of which the following is a specification.

This invention relates to velocipedes having two rear wheels, to the axle of which is attached a seat-supporting frame, and a front 10 wheel, journaled in a frame, is hinged to the seat-supporting frame.

The invention has for its object to provide certain improvements relating to the construction of the seat-supporting frame, whereby the 15 same is made strong, light, and graceful, and to the means for securing the propelling cranks to the front wheel, whereby a strong and durable connection is insured and the cranks are securely held in their proper relative positions.

To these ends my invention consists in the improvements which I will now proceed to describe and claim.

Of the accompanying drawings, forming a 25 part of this specification, Figure 1 represents a side elevation of a velocipede embodying my improvements. Fig. 2 represents a perspective view of the seat-supporting frame, the seat, and the rear axle. Fig. 3 represents an 30 enlarged top view of the hub of the driving-wheel, and Fig. 4 represents an enlarged section on line $x-x'$, Figs. 1 and 3.

The same letters of reference indicate the same parts in all the figures.

35 In the drawings, A represents the seat-frame; B, the seat, and C the frame in which the driving-wheel D is journaled. The frame C is composed, as usual, of two vertical standards, $c-c'$, connected at their upper ends by a 40 transverse bar, d , having handles at its ends. The frames A and C are hinged or pivoted together at H, as usual, so that the frame C, with the driving-wheel, can turn freely. The seat-frame A is composed of two arched pieces, a 45 a' , rigidly secured together at their forward ends and rigidly attached to the rear axle, E, at their rear ends, and straight braces $a-a'$, secured to the arched pieces a at points near the ends of the latter, so as to hold the pieces a in 50 their arched form, as shown in Figs. 1 and 2. The seat B rests upon the arched pieces a near their forward ends. It will be observed that

each arched piece a and its brace a' constitute a truss capable of resisting a great degree of vertical pressure. I am therefore enabled to make the frame A of light and slender strips or pieces $a-a'$, (of wood, if preferred,) and at the same time obtain the necessary strength. The arched form of the pieces a gives the velocipede a resemblance to the bicycle now in general use, and also enables the seat to be supported at a point nearer the vertical plane of the axis of the driving-wheel than in three-wheeled velocipedes previously made.

65 Heretofore the seat-supporting frame has been composed of two straight bars or pieces extending directly from the point of connection with the frame C to the rear axle. It will be seen that the portions of said bars on which 70 the seat is supported are necessarily lower and farther back from the vertical plane of the axis of the driving-wheel than the corresponding portions of the arched pieces a .

I do not limit myself to the employment of 75 two trusses, as shown in Fig. 2, it being obvious that a single truss embodies the spirit of my invention. By bringing the seat forward, as described, the weight of the rider is supported more largely by the driving-wheel, 80 and the rear wheels are enabled to be made smaller.

The driving-wheel D is provided with a metallic hub, K, composed of three sections, 2 85 4. The section 3 is formed upon a pipe or box, 5, and the sections 3 4 have central orifices, and are placed upon said box, as shown in Fig. 4. The spoke-sockets are formed by coinciding 90 semicircular cavities in the proximate sides of said sections, as shown in Fig. 3. This sectional construction of the hub forms no part of my present invention.

The shaft of the cranks M M is formed in separate pieces N N', one of which has a reduced threaded end and the other a threaded 95 socket adapted to receive said threaded end. The parts N N' are inserted in the bore of the box 5 and screwed together therein, and are then rigidly secured to the box by keys O O, driven firmly into coinciding grooves in the 100 box and the parts N N'. By this construction the cranks M M and their shaft are virtually made integral with the hub, being attached thereto so firmly as to make accidental sepa-

ration or loosening impossible. I prefer to provide the parts N N' of the crank-shaft with fixed collars N² at opposite sides of the hub, although such collars are not essential. The parts N N' of the cranks are each made in a single angular piece without a joint. If desired, the parts N N' may be externally threaded and screwed into the bore of the hub and keyed, as described.

10 I claim—

- 15 1. A velocipede composed of the larger driving or steering wheel journaled in a frame, C, the smaller rear wheels on an axle, E, the inclined trussed seat-supporting frame A, pivotally connected to the frame C and rigidly attached to the rear axle, and the seat B, attached to the higher or front end of the frame A in close proximity to the frame C, as set forth.
- 20 2. In a velocipede having a larger driving-wheel journaled in a frame, C, and smaller rear wheels on an axle, E, the trussed frame A, composed of the curved bars *aa*, having means

at one end for a pivotal connection with the frame C, and adapted to be rigidly attached 25 at their other ends to the axle E, and the straight braces *a'*, attached to the bars *a*, near the ends thereof, as set forth.

3. The combination of the metallic hub of the driving-wheel having a continuous tube 30 or box, 5, extending from end to end of the hub, the cranks M M, secured to each other within said box, and thereby prevented from independent longitudinal movement, and keys 35 O O, driven between the interior surface of the box and the exterior surfaces of the cranks, whereby the cranks are prevented from rotating independently, as set forth.

In testimony whereof I have signed my name to this specification, in the presence of two sub- 40 scribing witnesses, this 18th day of August, 1882.

STEPHEN H. KIMBALL.
